UNITED STATES PATENT OFFICE.

MAX HERMSDORF, OF ESSEN-ON-THE-RUHR, GERMANY, ASSIGNOR TO FRIED. KRUPP AKTIENGESELLSCHAFT, OF ESSEN-ON-THE-RUHR, GERMANY.

LOCKING DEVICE FOR GUN-CLOSURES.

No. 896,636.

Specification of Letters Patent.

Patented Aug. 18, 1908.

Application filed April 4, 1908. Serial No. 425,159.

To all whom it may concern:

Be it known that I, MAX HERMSDORF, a subject of the Emperor of Germany, and a resident of Essen-on-the-Ruhr, Germany, 5 have invented certain new and useful Improvements in Locking Devices for Gun-Closures, of which the following is a specification.

The present invention relates to the type 10 of wedge-closures for guns in which the opening and closing of the closure is effected by means of an operating screw mounted in the breech-block.

The invention has especially reference to 15 a locking device by means of which the crank of this type of gun-closures can be secured in the position of rest.

In accordance with the invention that 20 part of the locking device, which is adapted to engage with the locking part on the crank, is movably arranged on the breech-block in such a manner that it automatically leaves its locking position during the first part of the opening movement of the breech-block, 25 and is automatically returned to its locking position towards the end of the locking movement of the breech-block. Locking devices which act in a similar manner are known in screw closures for guns.

30 One embodiment of the invention and some parts of a wedge-closure are shown in the accompanying drawings, Figure 1 being a side view of the closed closure, and Fig. 2 being a section on line 2—2, Fig. 1, looking 35 from above. Figs. 3—5 are views on an enlarged scale, Fig. 3 showing a part of Fig. 2; Fig. 4 being a section on line 4—4, Fig. 1, looking from the left, and Fig. 5 being a view corresponding to Fig. 4 but showing a different relative position of the parts.

Through the medium of an operating screw B the wedge breech-block A can be displaced in the wedge-shaped opening of the breech. The operating screw is rotatably but 45 non-slidably mounted in the breech-block and is provided with a two-armed crank E. The thread b¹ of the operating screw engages with a nut D (Fig. 1) embedded in the breech and extends in such a manner that a little 50 more than one complete revolution of the operating screw is required for opening the breech, it being necessary to turn the crank E in the direction of the arrow x (Fig. 1) in order to open the breech.

55 A locking device F G serves for securing

the crank E in the position which it assumes when the closure is closed. One part of the locking device is formed by a latch F which is rotatably mounted on a bolt H at the free end of one of the arms of the crank E. The 60 latch F is provided with a nose f¹ (Figs. 4 and 5) and is under the action of a spring f² which tends to hold the latch in the locking position. The nose f¹ is provided with a locking face f⁴ and with an inclined face f⁵. 65 A handle J, which is jointed to the crank E through the medium of the bolt H and which is provided with a stop i¹, serves for withdrawing the latch F from locking position. The stop i¹ is adapted to coöperate with a stop f³ on the latch F. The other part of the locking device is formed by a bolt G which is 70 slidably mounted in the rim-plate a¹ of the breech-block and in a projection a² on the rim-plate a¹. The bolt G is arranged in such 75 a manner that it lies against the breech C of the gun-barrel when the closure is closed. When the closure is being opened the bolt G can move axially from this position under the action of a spring g² to such an extent 80 that a nose g¹ provided on the bolt G passes out of the path of the nose f¹ of the latch F which is in the locking position. The nose g¹ is provided with a locking face g⁴ and an inclined face g⁵. A screw K which is ar- 85 ranged in the housing for the bolt G and which engages in a groove g³ in the bolt, limits the axial movement of the bolt G and secures it against turning in its housing.

When the closure is closed the several 90 parts assume the position shown in Figs. 1 to 4, and the locking device F G secures the crank E and consequently also the operating screw B against turning to open the closure. The operating screw is prevented from turn- 95

ing in the other direction because the breech-block lies with its rim-plate a¹ against the breech.

To open the closure the operator takes hold of the handle J and turns it towards the 100 gun-barrel. Through the medium of the stops i¹ f³ the turning movement of the handle J is partaken of by the latch F whereby the locking face f⁴ of the nose f¹ passes out of engagement with the locking face g⁴ of the 105 nose g¹ of the bolt G. The crank E is thereupon turned in the direction of the arrow x (Fig. 1) which causes the breech-block to pass out of the breech of the gun-barrel.

When, directly after the turning move- 110

ment of the crank E is started, the rim-plate a^1 of the breech-block reaches the position shown in Fig. 5 relatively to the breech C, the bolt G is not any longer in abutment with the breech and under the action of the spring g^2 it has moved in its housing to such an extent that its nose g^1 has passed out of the path of the nose f^1 of the latch F, the latch being in the locking position. While the 10 crank E is being turned—as above-mentioned more than a complete rotation of the operating screw is required for opening the closure—it is therefore not necessary to hold the latch F in the withdrawn position nor is 15 it necessary to again withdraw the latch when, after a complete revolution of the crank, the crank-arm carrying the latch F has reached the position shown in Fig. 5 relatively to the bolt G.

20 The closing of the closure is effected by turning the crank E in the direction opposite to the arrow x. Towards the end of the closing movement of the breech-block the bolt G will be returned to locking position by coming into abutment with the breech C. When the bolt G has almost reached this position the nose f^1 of the latch F, which is in locking position, hits with its inclined face f^3 the inclined face g^3 of the nose g^1 of the bolt G. 25 During the last part of the turning movement of the crank E the latch F will therefore yield to the bolt G. However, in the moment the rim-plate a^1 has come into abutment with the breech and the bolt G has 30 attained its locking position the nose g^1 of the bolt G releases the latch F and the latch moves forwardly to bring its nose f^1 under the nose g^1 . The locking device F G is then again interlocked and the closure is secured 35 against accidental opening.

40 Having described the invention what is claimed and desired to be secured by Letters Patent is:

1. In a gun, the combination with the 45 wedge breech-block and its operating screw having a crank, of a locking device for locking the breech-block in the closed position; said locking device consisting of two parts adapted to interlock, one of said parts being carried by the breech-block and the other being carried by the crank of the operating screw and one of the parts automatically moving out of locking position when the crank is turned to open the breech-block.

50 2. In a gun, the combination with the wedge breech-block and its operating screw having a crank, of a locking device for lock-

ing the breech-block in the closed position; said locking device consisting of two parts adapted to interlock, one of said parts being 60 carried by the breech-block and the other being carried by the crank of the operating screw, and one of the parts automatically moving out of locking position when the crank is turned to open the breech-block, 65 and automatically returning to locking position towards the end of the turning movement of the crank that closes the block.

3. In a gun, the combination with the wedge breech-block and its operating screw 70 having a crank, of a locking member on said crank, a second locking member on the breech-block normally held interlocked with said first-named locking member to lock the breech-block in the closed position, and means whereby said second locking member is automatically moved out of locking position when the crank is turned to open the breech-block.

4. In a gun, the combination with the 80 wedge breech-block and its operating screw having a crank, of a locking member on said crank, a second locking member on the breech-block normally abutting against a fixed part of the gun to be held thereby in 85 interlocking engagement with said first-named locking member to lock the breech-block in the closed position, and means whereby said second locking member is moved out of locking position when the 90 crank is turned to open the breech-block and move the locking member out of abutment with said fixed part.

5. In a gun, the combination with the 95 wedge breech-block and its operating screw having a crank, of a locking member on said crank, a second locking member mounted to slide in the breech-block and normally abutting against the breech to be held thereby in 100 interlocking engagement with said first-named locking member to lock the breech-block in the closed position, and a spring acting on said second locking member to move the member out of locking position when the crank is turned to open the breech block and 105 move said second locking member out of abutment with the breech.

The foregoing specification signed at Dusseldorf, Germany, this 21st day of January, 1908.

MAX HERMSDORF.

In presence of—

PETER LIEBER,
WILHELM FLASCHE.
